UNITED STATES PATENT OFFICE

HARRY GLAENZER, OF PHILADELPHIA, PENNSYLVANIA

ASH PAN FOR LOCOMOTIVES

Application filed December 14, 1931. Serial No. 581,029.

My invention relates to certain improvements in locomotive ash pans. These ash pans are secured to the underside of the fire box of the locomotive so as to receive ashes discharged from the grates. The fire boxes of locomotives are at the present time very wide and the usual practice is to provide a central fire box having wide flanges which extend under the entire grate so that the ashes falling from the outer portions of the grates will be directed to the central ash pan. These side flanges are of necessity made with very little incline so that the ashes accumulate on these side flanges instead of flowing by gravity into the central collecting portion of the ash pan, and means has been provided for pushing the ashes from the inclined flanges to the central collecting portion of the ash pan, but even then the men have to use pushers to dislodge the ashes.

One object of my invention is to so design the ash pan, which is attached to the fire box, that the ashes passing through the grate at the side of the fire box will drop onto comparatively steep outwardly inclined surfaces or onto ash hoppers carried by the truck, which is located under the fire box.

Another object of the invention is to provide means for hanging the ash pan by links to the frame structure.

A further object of the invention is to support the intermediate members of the grate structure by the upper section of the ash pan.

The truck having the ash hoppers mounted thereon is fully set forth and claimed in application filed by me on the 27th day of November, 1931, Serial No. 577,622.

In the accompanying drawings:

Fig. 1 is a plan view of my improved ash pan for locomotives;

Fig. 2 is a side view, the mud ring to which the upper section of the ash pan is secured being shown by dotted lines;

Fig. 3 is a transverse sectional view on the line 3—3, Fig. 2, showing the truck in dotted lines;

Fig. 4 is a side view showing the means for operating the gates of the several chutes of the ash pan; and

Fig. 5 is a plan view of the lower section of the ash pan.

Referring to the drawings: 1 illustrates the mud ring of the fire box of the locomotive. 2—2 are the grate bars and 3—3 are the intermediate supporting members for the grate bars. 4 is the upper section of the ash pan, which is flanged at each side and at the ends as at 5, the flanges being secured to the mud ring of the fire box.

The upper portion of this section 4 of the ash pan is inclined to conform to the incline of the lower portion of the fire box. This upper section has a longitudinal depending flange 6 at each edge as shown in Fig. 3, and the body portion of the pan is inclined as at 7 from points α at each side of the center towards the center of the pan, in which there is a longitudinal opening 8 extending substantially the full length of the ash pan, and the inclined portions merge into longitudinal flanges 9—9, forming the walls of the longitudinal opening 8.

The ash pan is inclined outwards from the point α , as shown at 10, to form chutes for the ashes that drop from the outer portions of the grates 2—2. This flange terminates short of the depending flange 6 at each side, leaving longitudinal openings 11 for the discharge of ashes from the inclined chutes 10 and directly from the outer ends of the side grates 2 into hoppers 12 mounted on a truck 13 shown by dotted lines in Fig. 3.

This particular truck is set forth and claimed in the application referred to above. 14 is the front wall of the upper section of the ash pan. This wall is inclined as shown and 15 is the inclined rear wall of the ash pan. In this inclined wall 15 is a recess 16 for stoker mechanism in the present instance.

The upper section 4 of the ash pan is supported by the mud rings 1 and carries the intermediate supports of the grates 2. 17 is a link member having a cross bar 18 and at each end of this link are arms 19 which are coupled to the grate supporting bars 3 by pins 20, and extend into pockets 21 in the ash pan and are pivotally connected to the ash pan by pins 22 so that the upper portion of the ash pan properly supports the interme-

diate frames of the grate of the locomotive.

23 is the lower section of the ash pan, in which are three hoppers 24 in the present instance. This lower section 23 is comparatively narrow and extends between the wheels of the truck and rear frame of the locomotive, and the side members 25 of this lower section 23 extend on the outside of the flanges 9 of the upper section. The lower section receives the 10 ashes that are discharged through the central opening 8 in the upper section 4 of the ash pan. The three hoppers 24 are spaced apart as shown in Figs. 2 and 4, and the lower open ends of the hoppers are inclined at 26. The 15 openings in the bottom of the hopper are closed by gates 27 which fit against the inclined portions 26 of the hoppers. The hoppers are reinforced in the present instance by ribs 28, as this section of the hopper is preferably made as a casting as well as the upper section 4. The lower section 23 of the hopper is hung by links 29 from the longitudinal members 30 of the rear frame of the locomotive. These members in the present instance 20 are channel shaped in cross-section but they may be of any shape without departing from the essential features of the invention.

The links are connected to the lower section 23 by pins 31 and to the frames 30 of the locomotive by pins 32. This construction allows a limited amount of movement of the lower section, which is essential. In the present instance the lower section 23 is made in two parts. One part has two hoppers and the 35 other a single hopper and each part has a vertical transverse flange 33, the two flanges being secured together by bolts 34, but it will be understood that in some instances the lower section of the hopper may be made as a single casting. The hoppers 24 of the lower section are spaced apart so as to allow for clearance of the axles 35 of the truck 13 of the locomotive and the walls of the hoppers are inclined as shown in Figs. 2 and 4, so as to allow the 40 ashes to freely flow into the hoppers and when the doors are opened the ashes will be readily discharged therefrom. In the present instance the doors are opened and closed by means of a hand-lever 36, secured to a rock 45 shaft 37 mounted in bearings 38 on the forward end of the section 4 of the ash pan. Each gate 27 is hung by links 39 to pivot pins 40 mounted in bearings 41 on the lower section 23 of the hopper. Secured to the rock 50 shaft 37 are two arms 37a, which are connected by links 42 to one arm of a lever 43 on each side of the lower section of the ash pan. The levers 43 are mounted on a pivot shaft 44 carried by bearings 45 projecting from the forward end of the lower section 23 of the ash pan. The lower arm of each lever 43 is forked and each lever is pivotally connected to a floating lever 46 by a pin 47. One arm of the floating lever 46 is connected by 55 a rod 48 to the forward gate 27 of the ash pan,

while the other end of the lever 46 is connected by a long bar 49 to a floating lever 50, one arm of this lever being connected to the gate of the intermediate ash pan and the other arm of the lever 50 is connected by a rod 51 to the rear gate. This gate opening mechanism may be modified without departing from the essential features of the invention.

By the above description it will be seen that the ash pan is located directly under the 70 grates of the fire box and that the upper section has inclined surfaces which direct portions of the ashes through a central opening 8 into the lower section 23 of the ash pan, where the ashes accumulate in the hoppers 24. The ashes which pass through the grates near the outer sides of the fire box fall on the outer 75 inclined surfaces 10 of the upper section 4 of the ash pan and are discharged into the hoppers 12 mounted on the rear truck of the locomotive, while the ashes passing through the grates at the extreme sides of the fire box fall directly through the openings 11 into the hoppers 12.

The lower section 23 of the ash pan supports the central portion of the upper section which rests upon internal flanges 52 on the side members 25 and is preferably secured to said side members by bolts, as shown in Fig. 3. In some instances the flanges may be dispensed with when bolts are used.

By the above construction all ashes discharged from the grates either pass directly into the hoppers of the lower section or flow into the said hoppers or pass into the hoppers mounted on the truck, and the inclines are at such an angle that no ashes will remain on the inclined surfaces of the upper ash pan.

I claim:

1. The combination in a locomotive fire box, of an ash pan located under the fire box, said ash pan having a central hopper and side inclined surfaces, and having side openings at the outer edges of said inclined surfaces whereby the ashes from the outer end sections of the side grates will be directed through the openings.

2. The combination in a locomotive, of a fire box; a truck located under the fire box and having ash hoppers at each side thereof; grates in the fire box; and an ash pan under the grates having a central discharge opening and side discharge openings, said side discharge openings discharging ashes that pass through the grates at each side into the ash hoppers on the truck.

3. The combination in a locomotive, of a fire box; grates therein; an ash pan comprising a central hopper section; and an upper section, said section having inclined surfaces discharging into the central section and outside inclined surfaces and having openings beyond said side inclined surfaces; a truck having ash hoppers at each side, into which ashes, passing through the grates at each side

- of the fire box are discharged, some of said ashes falling directly through the opening into the hoppers on the trucks, while others fall upon the side inclined surfaces, which 5 discharge the ashes through the side openings into the hoppers of the truck.
4. The combination in a locomotive, of a fire box; grates mounted in the fire box; and upper and lower ash pans, the upper ash pan 10 being connected to the locomotive structure and having a central longitudinal opening and side longitudinal openings and having two sets of inclined surfaces, the central set of inclined surfaces discharging through the 15 central opening and the outer surfaces discharging ashes through the side openings.
5. The combination in a locomotive, of a fire box; grates mounted in the fire box; intermediate supports for the grates; upper 20 and lower ash pan sections; links connecting the upper ash pan sections with said intermediate supports for the grates, said upper section having a central longitudinal opening and having two inclined surface 25 directing ashes falling from the grate to the central opening, the lower ash pan section having a series of hoppers in which the ashes collect, the upper ash pan section having a longitudinal opening at each side, and having 30 inclined surfaces arranged to direct the ashes falling from the outer portions of the grate through the side openings.
6. The combination in an ash pan for locomotives made in two sections, of means for 35 hanging the upper section from the fixed structure of the locomotive, said ash pan extending under the grate of the fire box; a lower hopper section; and links connecting the lower hopper sections with the frame of the locomotive.
7. The combination in an ash pan for locomotives, of an upper section having a central longitudinal opening and inclined surfaces at each side of the opening arranged 45 to discharge ashes into the central opening and having outer inclined surfaces, the incline of the outer surfaces being opposite to that of the inner surfaces; means for connecting the ash pan with the body of a locomotive; a lower hopper section arranged to receive ashes from the upper section through the central opening; and links connecting the lower section with the main frame of the locomotive.
- 55 8. The combination in a frame of a locomotive, of a fire box; grates in the fire box; intermediate supports for the grates; an ash pan made in two sections; links connecting the upper section with the intermediate supports for the grates; and links connecting the lower section with the frames of the locomotive.
9. The combination in a locomotive, of a frame; a fire box having a mud ring; grate 65 bars in the fire box; intermediate supports
- for the grate bars; an ash pan comprising upper and lower sections, the upper section being secured to the mud ring; links connecting the intermediate supports for the bars of the grate with the central portion of the upper section of the ash pan, said upper section having a central longitudinal opening and having inclined side portions, the lower ends of the said portions terminating at the longitudinal opening so as to direct ashes falling from the central portion of the grate into and through the opening; longitudinal openings at each side of the said upper portion of the ash pan, said ash pan having side inclined sections for directing ashes through the said openings; links connecting said lower section with the longitudinal frames of the locomotive, said lower section having a series of hoppers; and gates for said hoppers.
10. The combination in an ash pan for locomotives, of a fire box; grates mounted in the fire box; intermediate supports for the grates; an ash pan under the grates; and links connecting the ash pan with the supports for the grates.
11. The combination in a locomotive, of an ash pan made in two sections; means for hanging the upper section from the fixed structure of the locomotive; a lower hopper section; and links connecting the lower hopper section with the frame of the locomotive.
12. The combination in a locomotive, of a sub-frame; a fire box; a grate structure therein having intermediate supporting members for the grates; an ash pan comprising upper and lower sections and located under the grate structure, the upper section of the ash pan being secured to the fire box; supporting links connecting the upper section of the ash pan to the intermediate supports for the grate bars; and links connecting the lower section with the frame of the locomotive, the upper section having a central discharge opening arranged to discharge ashes into the lower section.
